UNITED STATES PATENT OFFICE

WILLIAM G. VENARD, OF LOS ANGELES, CALIFORNIA

FORM FOR BUILDING COLUMNS AND BEAMS

Application filed August 6, 1930. Serial No. 473,380.

This invention relates to improvements in building forms and particularly to forms for making beams and columns of buildings in the course of erection, especially plastic columns and beams.

One of the objects of the present invention is to provide a simple, efficient and inexpensive concrete beam and column building form designed along lines that assures the saving of both time and labor.

A further purpose of this invention is to provide beam and column forms constructed of extensible, adjustable parts so that the size of the form enclosure may be varied at will.

Another object thereof is to provide beam or column forms built up vertically and transversely from a series of replaceable and interchangeable metal plates so arranged and constructed as to avoid the necessity of the form having to be cut to predetermined widths and sizes, and permitting a number of metal plates to be set up quickly for the same purpose.

A further object of this invention is to provide a series of interchangeable, adjustable battens or bracing members designed to be lengthened or reduced in length accordingly as the width of the form walls vary.

A still further object of this invention is to provide a beam form extension designed to be built onto and removably connected to the upper end of the column form to allow the beam and column to be built from a unit form enclosure.

Another object of this invention is to provide a novel form of means for bracing the coinciding edges of superimposed metal plates of a form wall structure to assure proper clamping pressure being exerted along these marginal parts of sectional walls, and to this end each batten or bracing unit consists of two parts, one part telescoping in the other part, and each part consists of two elongated parallel sills with cross arms interconnecting them into a rigid whole. In the spaces between the sills of the wider parts of each bracing unit are located channel-shaped metal rests, their edges of the two arms thereof overlying the coinciding edges of meeting wall plates in a plane at right angles to the

sills of the brace members which overlie these same surfaces longitudinally. A series of T-shaped bolts are employed in a manner that their cross heads may directly overlie and bear upon the opposing sills of the narrow parts of each brace member, which are slidably adjustable in the wider parts of the same brace member, while other of these bolts have their cross heads overlying the channel shaped metal rests since they cannot directly span the sills of the wider brace parts. The shanks of the T-shaped bolts are screw-threaded and they are tapped into the coinciding edges of the plates with thumb nuts engaged upon their inner ends to clamp the heads of these bolts and draw the battens or brace members under pressure upon these plates.

I also provide novel means for locking the corner-arranged brace members or units one to the other under mechanical frictional pressure for the purpose of assuring that the corners of the form will be held in rigid relationship and against buckling.

With the above and other objects in view my invention consists in the combination, arrangement and details of construction disclosed in the drawings and specification, and then more particularly pointed out in the appended claims.

In the drawings, which are merely illustrative of my invention, and in which similar reference characters designate similar parts throughout the respective views,

Figure 1 is a fragmental front elevation of a form wall made of two superposed plate sections, showing the battens for holding their coinciding edges together,

Figure 2 is a sectional elevation, partly in section, of a beam-making form attachment for a wall of the column form,

Figure 3 is a fragmental view of portions of the front walls of two coinciding metal plates,

Figure 4 is a detail sectional view showing endwise two vertically arranged wall plates, showing a batten overlying both of them, with a special bolt-head rest in this batten,

Figure 5 shows a similar arrangement of

parts as in Figure 4 but here the batten is shown of a lesser width.

Figure 6 is a fragmental section of a wall of a column form showing in front elevation 5 the beam attachment therefor,

Figure 7 is a vertical sectional elevation of a bolt-head rest, to be described,

Figure 8 is a perspective view of a beam-making attachment for a column-making 10 form,

Figure 9 is a bottom plan view of Figure 7,

Figure 10 is a top plan view showing two corner sections of a column form, with the batten locking means,

15 Figure 11 is a top plan view, partly in section, of a portion of a pilaster form showing its location with respect to wall posts,

Figure 12 is a perspective view of overlapping form sections,

20 Figure 13 is a sectional view of a corner part of a form showing upon a wall thereof in top plan a closure plate for a débris-removing opening,

Figure 14 is a plan view of a column making form showing the rectangular enclosure 25 constructed from rightangular plates,

Figure 15 is a sectional plan view of a wall of a column form showing the batten arrangement therefor,

30 Figure 16 is a front elevation of a wall plate showing the closure plate closed in the débris-removing opening, and

Figure 17 is a view similar to Figure 16 but showing the closure plate in open position.

35 In the drawings any number of metal thin plates are employed to produce the form for making a post or column or beam. It is preferred that the several wall sections to make up this form such as the plates A, B, C, etc., 40 be rightangular in cross-section each having the walls 10 and 11. In Figure 12 it is shown how these rightangular plates overlie one upon the marginal edge of the other so as to be adjustable to vary the width of the wall of 45 the form which they will serve to make. Figure 14 shows flanges 12, 13 formed upon the corner parts of each rightangular plate A, B, C, and D respectively, the terminals 10A of the walls 10 of which plates project 50 beyond the adjacent extreme end of the flange 12, so these parts are shouldered one against the other. Here the flanges serve to reinforce the rightangular plates giving them more strength and durability.

55 Figure 14 shows how these plates are arranged to produce a rectangular enclosure for building a concrete column or post therein. Since the sheet metal plates will be of inappreciable thickness their overlap will 60 hardly interfere with the flush continuation of each side of the completed column.

In Figure 11 the method of securing the form plates about wall posts is shown where the wall is to be built upon or about the 65 columns. Here it is observed that the walls 11

of each rightangular plate may be formed with a rightangular flange at the end opposite to, and parallel with the wall 10 of each plate. The wall-making plates 20 will have their inner marginal portions overlapping the wall 70 posts 18 while the flanges 19 will overlap these marginal portions of the wall plates 20. Otherwise the walls 10 of both plates will adjustably overlap so as to provide one wall and part of rightangular walls of the column. 75

The rectangular enclosures thus produced will be caused to build up a vertical structure and this will or may be done by setting the lower edges of upper plates upon the upper edges of lower plates to produce a flush wall as shown in Figure 1, where A and T represent the walls as they are superimposed and where 14 designates the coinciding edges of these superimposed plates. In order to hold the superimposed walls of the proposed 80 column form at any height where placed vertically it is designed to employ bracing members or units in the form of battens now to be described.

In Figure 1 it will be seen that each batten 90 or bracing unit consists of two parts, one part being narrower than the other and telescoping adjustably in the other part. Each part is similarly constructed as follows. The wider part of the adjustable batten consists 95 of the elongated spaced apart parallel sills 21, 22 with the intervening space 26, the cross bars 28 connecting these sills together. The narrower part of the batten consists also of parallel spaced sills 24, 25, with the intervening space 27, and the cross bars 28 connecting the sills in a whole. The batten parts will overlie the marginal coinciding portions or edges of the plates A and T in such a manner that the longitudinal sills 21, 24 of the 100 adjustable parts of the batten will overlap plate A, while the sills 22, 25 of these same parts will overlie the plate T. In order to hold the battens under mechanical pressure against plates A and T the following means 105 is employed.

It is desired to employ any of a number of similarly sized and shaped T-shaped bolts with suitable cross-heads as the means of fastening the battens removably against the several 110 walls made by the form for building a column.

A series of channel-shaped metal rests are provided, as shown in Figures 7 and 9, where it will be seen that the top is designated 29, and the rightangular parallel sides are desig- 115 nated 30, 31, while the hole in the top is designated 32. The rests are stationed in such a manner that the rightangular walls 30, 31 of each rest will bridge the coinciding edges 14 of the superimposed form plates A and T 120 transversely of the battens and at right angles to the line of overlapping of the sills 125 of the battens. The rests will fit only in the space 26 between the sills 21, 22 of the wider 130 part of the movable batten sections and are

135

of a width equal to that of the cross-head 32' of the T-shaped bolts 34, which are employed as fasteners for the battens. Thus it will be seen that these cross-heads 32' are just long enough to span the sills 24, 25 of the narrower batten section but not wide enough to bridge the sills 21, 22 of the wider part, hence the necessity of using the rests to make them provide a rigid backing for the cross heads 32' of the bolts to engage in their function of drawing the battens against the plates A and T etc.

In Figure 3 it will be seen that the coinciding edges of plates A and T are formed with bolt-hole recesses 15 and 16 respectively, designed, when these plates are arranged in superimposed relation, to provide bolt holes 17, so after the cross-heads of the bolts overlie the sills 24, 25 and the tops 29 of the rests, the bolts will pass thru these bolt holes 17 and project beyond the opposite faces of the plates A and T etc. Thumb nuts 36 may now be screwed home upon the screw-threaded terminals 35 of these bolts, and clamp the battens against the plates. With all parts thus arranged, the nuts could be loosened sufficiently to allow the batten parts to be moved in and out one relatively to the other to be made coextensive with the width of the form wall plates.

In order to apply suitable mechanical pressure against the corners of the form wall plates whereby they are interlocked at these points rigidly and against buckling or collapse I employ means to lock the battens that are arranged at right angles, at the corners of the form, together. For this purpose a handle 37 formed with an elongated slot (if desired to allow clearance against the bolt 34 that might project therethrough is desired) is provided, which has its inner end 37a pivoted upon a pin 38, mounted operatively in the sills 24, 25 of the batten section. This handle may thus be swung inwardly in the recess 27 of this batten section as shown in Figure 10 in dotted lines, the purpose in doing so being to actuate a saddle member now to be described.

The saddle locking member is composed of two parallel arms 40, 41 pivoted upon a pin 39 connected to the lever 37 at its inner end, while another locking pin 42 is connected to the free ends of arms 40, 41 so as to rigidly span and connect the same. The ends of the sills 24, 25 of the batten shown in end elevation in Figure 1 are provided with a corner notch shown at 43 in Figure 10, and in this notch the pin 42 may extend when the handle is in dotted line position shown in Figure 10. It will now be seen that guide 56 secured rigidly to the bottom limits the back movement of lever handle 37, and as the handle moves backwardly from dotted line position to full line position shown in Figure 10 the arms 40, 41 of the saddle piece are drawn back-

wardly sufficiently to force the pin 42 into recess 43, and to exert a pressure upon the batten shown endwise in Figure 1, effective to lock this batten to the batten shown overlapping form plates A and T in Figure 1. In this manner it is assured that the corner marginal edges of the right angularly disposed form walls will remain rigidly in proper place.

It may be desired to provide beam-making attachment to the column forms so that the overhead horizontal beam may be molded at the same time with the supporting columns or posts therefor. For this purpose a specially constructed form is furnished shown particularly in Figure 8. Here there is disclosed a channel-shaped member composed of the trapezoidal-shaped parallel walls 46, and 47 and the inclining bottom plate or wall 45, there being an outturned right-angular flange 48 and 49 formed respectively upon the walls 46, 47 of this beam-forming member. There are also right angular flanges 50 formed upon the walls 46 and 47 respectively, disposed at right angles beneath the flanges 48, 49, and these last-named flanges project below the lower edges of the side walls. The bottom wall 45 is formed at its rear end with a depending hook flange 51.

From Figure 2 it will be seen that the bottom plate 45 is hooked over the upper edge of the recess 52 formed in the form wall plate 44. The flanges 49, 50' as shown in Figure 6 may overlie the edges of portions 44A of the form wall plate 44, and now fasteners 53 will secure flanges 50 to this wall. The use of the flanges 49, 50' is optional. In this way the beam-making form will permit the beam and column to be molded in one continuous operation.

I also provide an effective means of blowing or sweeping out dirt, and débris that may accumulate in the completed form and for this purpose I form a hole 52' in the bottom of any form plate, and a closure plate 55 having a handle 56 will be slidably and frictionally guided in the guide tracks 54 formed integrally upon the opposing edges of this recess or hole 52'. In this way when the closure plate is raised access is given into the interior of the form whereby a hose may sprinkle water into the form to wash away dirt and similar or foreign particles or the dirt may be removed from this hole in any other effective manner.

I do not intend to limit myself to the exact details of construction but aim to cover all variations falling within the purview of the appended claims.

What I desire to claim and seek protection on is as follows:

1. A form as described consisting of a series of rightangular corner plates, arranged in adjustable relation and in overlapping position one against the other to provide a rec-

- 10 tangential enclosure, a plurality of similar enclosures being superimposed one upon the other so that their edges coincide, a series of rigid telescoping brace members arranged upon all sides of the enclosures in a manner to partly overlap the coinciding edges of the superposed plates, and manually operated locks controlled to connect the pairs of right-angularly disposed brace members at the corners of each enclosure to hold all brace members in place.
- 15 2. A form as described consisting of a series of collapsible rectangular enclosures built up from metal plates, said plates being arranged in superimposed relation to build a vertical structure, a separate rigid extensible brace overlapping the coinciding edges of each wall formed by superimposed plates, bolts tapped thru the brace members and passing thru the coinciding edges of said superimposed plates, means carried by parts of the adjustable brace members designed to press said brace members against the coinciding edges of the plates as said bolts are driven home, nuts clamping the bolts upon said plates, and means for manually exerting a pressure upon all of said brace members at the corners of the enclosures to assure rigid locking of all plates together.
- 20 30 3. In a device as described, in combination a series of vertical walls, each composed of a plurality of plates arranged in superimposed relation flush with each other, bracing units arranged transversely of each pair of superimposed plates, and arranged to overlap the coinciding edges of each pair of superimposed plates, each unit consisting of a pair of telescoping adjustable clamps of which one clamp is wider than the other, each clamp of each unit composed of a pair of longitudinal parallel sills interconnected transversely, a series of T-shaped bolts having screw threaded shanks, some of which have their heads overlapping the sills, at right angles, of the narrow clamp of each unit and have their shanks projecting thru the coinciding edges of plates, channel shaped rests overlapping with their parallel arms the coinciding edges of the plates and fitting in the space between the sills of the wider clamps of the units, others of said T-bolts having their heads overlapping the tops of these channel shaped rests, and having their shanks tapped thru said tops and passed thru the coinciding edges of plates, and thumb nuts screwed home, from the opposite sides of said coinciding plates, upon said bolts to draw the units under pressure against the plates.
- 35 40 45 50 55 60 65 70 75 80 85 90 95 100 105 110 115 120 125 130 135
4. In a device as described, in combination walls of a building form consisting of metal plates arranged in superimposed relation to build vertical structures, the coinciding edges of each pair of superimposed plates having complementary notches producing bolt holes, extensible brace members overlapping each pair of superimposed plates so as to partly overlie the marginal edge of each plate, nuts clamping the plates, bolts having cross heads overlapping the movable members of each brace member and receiving said nuts in screwed relation, said bolts passing thru said bolt holes of the plates, and means whereby upon loosening the nuts, the members of each brace may be extended.
5. In a device of the kind described, in combination a rectangular form having four walls, means whereby the walls may be extended adjustably so as to vary the size of the enclosure of the form, a plurality of brace members arranged in overlapping position upon each wall of the form, each form wall being composed of a plurality of superimposed sections the coinciding edges of which are overlaid by said brace members, means whereby said brace members may be adjusted variably to the varying widths of the form walls, means independent of the brace members and enclosed by the latter for overlying the coinciding edges of said wall sections in a plane at right angles to the line of overlapping of the brace members upon said walls, and removable fasteners exerting pressure upon the last-named means and upon the brace members.
- In witness whereof he has hereunder set his hand this 25th day of June, 1930.
- WILLIAM G. VENARD.
